(Cl. D83—1)

To all whom it may concern:

Be it known that we, Charles F. Hagemeyer and Roland N. Latina, are citizens of the United States and residents of the county of St. Louis, State of Missouri, and the city of Belleville, county of St. Clair, and State of Illinois, respectively, have invented a new, original, and ornamental Design for a Face Guard, of which the following is a specification, reference being had to the accompanying drawing, forming a part thereof.

Fig. 1 is a side view of the face guard showing our new design;

Fig. 2 is a bottom view of the face guard;

Fig. 3 is a front view thereof;

Fig. 4 is a rear view thereof; and

Fig. 5 is a vertical sectional view of the face guard seen along line 5—5 in Fig. 4.

We claim:

The ornamental design for a face guard, substantially as shown.
